PISTOL TOY

Roy Dee Griffin, Sr., 4025 Terrace St.,
Amarillo, Tex. 79109

Filed Oct. 12, 1970, Ser. No. 25,446

Term of patent 14 years

Int. Cl. D21—01

U.S. Cl. D34—15

FIG. 1

FIG. 2

FIG. 3

FIG. 4

FIG. 1 is a side view of the pistol toy as seen along the direction of arrow 1A of FIG. 3.

FIG. 2 is a front end view of the pistol toy shown in FIG. 1 along the direction of the arrow 2A of FIG. 1.

FIG. 3 is a rear end view of the pistol shown in FIG. 1 along the direction of the arrow 3A of FIG. 1.

FIG. 4 is an oblique view looking forward and downward at the pistol toy of FIG. 1.

I claim:

The ornamental design for a pistol toy, as shown.
